UNITED STATES PATENT OFFICE

ROBERT E. WAWROUSEK, OF BROOKLYN, NEW YORK

DESIGN FOR COMBINED AUTOMOBILE RADIATOR AND LAMP CASINGS

Application filed February 21, 1930. Serial No. 34,622. Term of patent 14 years.

To all whom it may concern:

Be it known that I, ROBERT E. WAWROUSEK, a citizen of Germany, and a resident of the city of New York, borough of Brooklyn, in the County of Kings and State of New York, have invented the new, original, and ornamental Design for Combined Automobile Radiator and Lamp Casings, of which the following is a specification.

Reference is had to the accompanying

drawing forming a part thereof, in which—

Figure 1 is a front view of a combined automobile radiator and lamp casings, showing my new design.

Figure 2 is a side view thereof.

I claim:

The ornamental design for a combined automobile radiator and lamp casings, substantially as shown.

ROBERT E. WAWROUSEK.
